UNITED STATES PATENT OFFICE.

AUGUST M. WARM, OF DANBURY, CONNECTICUT.

MACHINE FOR JACKING AND BRUSHING HAT-BODIES.

1,210,876.

Specification of Letters Patent.

Patented Jan. 2, 1917.

Application filed August 1, 1916. Serial No. 112,542.

To all whom it may concern:

Be it known that I, AUGUST M. WARM, a citizen of the United States, residing at Danbury, county of Fairfield, State of Connecticut, have invented an Improvement in 5 Machines for Jacking and Brushing Hat-Bodies, of which the following is a specification.

This invention relates to the manufacture 10 of hats and has for its object to provide a relatively simple and inexpensive machine which shall be easy to operate, and which by a mere change of brushes may be adapted to perform the jacking (i. e. nap-raising), dry brushing or wet brushing operations 15 quite as effectively as they can be done by hand and at a greatly reduced cost to the manufacturer.

With these and other objects in view, I 20 have devised the novel machine which I will now describe, referring to the accompanying drawings forming a part of this specification and using reference characters to indicate the several parts:

25 Figure 1 is a front elevation of my novel machine in the inoperative position; Fig. 2 an end elevation as seen from the right in Fig. 1; Fig. 3 a front elevation showing the machine in use; Fig. 4 an end elevation as seen from the right in Fig. 3; Fig. 5 an 30 end elevation as seen from the left in Fig. 1; Fig. 6 a vertical section on the line 6—6 in Fig. 3, looking in the direction of the arrows; Fig. 7 a vertical section on the line 35 7—7 in Fig. 3, looking in the direction of the arrows; Fig. 8 a detail sectional view on the line 8—8 in Fig. 7, looking in the direction of the arrows; Fig. 9 a fragmentary front elevation illustrating a variant form 40 of the invention, in which flat instead of rotary brushes are used, and Fig. 10 is a section on the line 10—10 in Fig. 9, looking in the direction of the arrows.

20 denotes the frame of the machine which 45 may be of any ordinary or preferred design and construction.

The hat bodies to be operated upon, indicated by 21, are placed upon a block 22 which is elongated in the direction of the 50 width of the machine and flattened upon the long sides, and is cone-shaped in cross section. The shape of the block will be readily understood from Figs. 1 and 6 which show it respectively in elevation and in cross section. This block is carried by a bar 23,

which is adapted to be moved vertically on ways 24 upon the frame. The bar, carrying the block, is reciprocated on the ways by means of crank rods 25 pivoted to the under side of the bar and to cranks 26 upon a shaft 60 27 journaled in the frame and in a bracket 28 shown as detached from the frame. The machine may be either operated by mechanical power or by hand power, as preferred.

65 29 and 30 denote fast and loose belt pulleys on the shaft over which a belt, not shown, passes.

31 denotes roller brushes carried respectively by shafts 32 and 33 journaled at the 70 upper ends of swinging arms 34 pivoted to the frame as at 35. The brushes are adapted to operate on opposite sides of a body upon the block. Each brush rotates downward and inward, and each brush shaft is carried 75 by two arms, one at each end of the machine. Brush shaft 33 is extended at the left end of the machine and carries a sprocket wheel from which a sprocket chain 36 extends over one wheel of a twin sprocket wheel rotating 80 on a short shaft 37 extending from the frame in alinement with the pivotal point 35 of the arm 34 which carries shaft 33 at the left end of the machine. A sprocket chain 38 passes over the other wheel of the twin 85 sprocket wheel and over a sprocket wheel 39 rotating on a short shaft 40 extending from the frame at the left end of the machine. Sprocket wheel 39 is secured to and carried by a sprocket wheel 41 rotating on 90 short shaft 40 extending from the frame, and sprocket wheel 41 meshes with a sprocket wheel 42 carried by crank shaft 27. Brush shaft 32 is extended at the right 95 end of the machine and carries a sprocket wheel from which a sprocket chain 43 extends over one wheel of a twin sprocket wheel rotating on a short shaft 44 extending from the frame in alinement with the pivotal point 35 of the arm 34 which carries 100 shaft 32 at the right end of the machine. A sprocket chain 45 passes over the other wheel of the twin sprocket wheel and over a sprocket wheel 46 on crank shaft 27 at the right end of the machine.

105 In order that crank shaft 27 and the parts operated thereby may be driven by hand power instead of mechanical power, I provide a crank wheel 47 which rotates on a short shaft 48 extending from the frame 110

and carrying a sprocket wheel 49 from which a sprocket chain 50 passes over a sprocket wheel on crank shaft 27 contiguous to sprocket wheel 46.

- 5 It will be understood that the brushing operation is performed by brushes rotating inward and downward and carried by pivoted arms and operating upon hat bodies carried by a block cone-shaped in cross section and having a vertical reciprocatory movement. In order that the brushes may move outward relatively to the body as the block moves upward, and vice versa, and thus maintain the same pressure of the brushes upon a hat body without regard to the position of the block relatively to the brushes, I provide at opposite ends of bar 23 wedges 51 shown as set over the bar and secured thereto by bolts passing through brackets 52. These wedges engage rollers 53 carried by the arms and swing the arms and with them the brushes away from the block. This outward movement of the arms and brushes is effected against the power of springs 54 connected to brackets 55 extending upward from the arms. The springs act to retain the rollers in close engagement with the wedges, whose angle of inclination corresponds with the block.
- 10 For the convenience of the operator in placing bodies upon the block and in shifting and removing them, I provide other wedges 56 carried by slides 57 which are adapted to reciprocate vertically on the ends 15 of the frame and to engage rollers 58 carried by the arms (on the opposite sides from rollers 53) and swing the arms open widely against the power of the springs carrying the brushes entirely away from the block.
- 20 The slides and wedges 56 are operated by means of levers 59 fulcrumed on the ends of the frame and loosely connected to the slides, the outer ends of the levers being connected by a hand bar 60 extending across the front 25 of the machine in convenient position for the operator.

In the form illustrated in Figs. 9 and 10, flat brushes, indicated by 61, are substituted for rotary brushes. These brushes 30 may be loosely attached to shafts 32 and 33 and the driving connections allowed to remain as shown or they may be rigidly attached to brush-carrying shafts, in which case sprocket chains 36 and 43 would be 35 removed.

Whether rotating or flat brushes are used, they may be made of bristles or wire, depending upon the operation to be performed. In handling large quantities of work, one 40 machine would ordinarily be used for jacking, another for dry brushing and another for wet brushing. In running through smaller lots of bodies, the same machine may be used for the successive operations by 45 simply changing the brushes. If two-part

brushes are used the changes may be made very quickly without removing the brush shafts. If the brushes are rigidly secured to the shafts, it would of course necessitate changes of brush shafts with the brushes.

The operation will be readily understood from the description already given. Briefly, the operator separates the brushes against the power of the springs by means of wedges 56, in the present instance operated by the hand bar. He then places a body on the block, lowers the wedges, and starts the machine. After operating as long as is required, the machine is stopped, the body shifted on the block and then brushed as before, these operations being continued until the desired effect upon the body is produced. The operation is the same whether the machine is driven by hand power or mechanical power.

Having thus described my invention I claim:

1. In a machine of the character described, in combination, brushes, swinging arms by which they are carried, and a vertically reciprocating block by which bodies are carried while being operated upon.

2. In a machine of the character described, in combination, brushes rotating inward and downward, swinging arms by which the brushes are carried and a vertically reciprocating block by which bodies are carried while being operated upon.

3. In a machine of the character described, in combination, brushes, swinging arms by which they are carried and a vertically reciprocating block, elongated in the direction of the width of the machine, flattened on opposite sides and cone-shaped in cross section, by which bodies are carried while being operated upon.

4. In a machine of the character described, in combination, brushes, swinging arms by which they are carried, a vertically reciprocating block by which bodies are carried while being operated upon, and means for causing the brushes to move outward relatively to the body as the block moves upward, and vice versa.

5. In a machine of the character described, in combination, brushes, swinging arms by which they are carried, a vertically reciprocating block by which bodies are carried, wedges engaging the arms for causing the brushes to move outward relatively to the block as the block moves upward, and springs for retaining the arms in engagement with the wedges.

6. In a machine of the character described, in combination, brushes, swinging arms by which they are carried, a block by which bodies are carried, a vertically reciprocating bar by which the block is carried, wedges carried by the bar and engaging the arms to swing the brushes outward.

5 relatively to the block, and springs for retaining the arms in engagement with the wedges.

7. In a machine of the character described, in combination, brushes, swinging arms by which they are carried, a block by which bodies are carried, a vertically reciprocating bar by which the block is carried, wedges carried by the bar and engaging the arms to swing the brushes outward relatively to the block, springs for retaining the arms in engagement with the wedges, and other wedges and operating means therefor, by which the arms are opened widely for convenience in placing, shifting and removing bodies.

8. In a machine of the character described, in combination, brushes, swinging arms by which they are carried, a vertically reciprocating block by which bodies are carried, means for causing the brushes to move outward relatively to the block as the block moves upward, and vice versa, and means for opening the arms widely for convenience in placing, shifting and removing bodies.

9. In a machine of the character described, in combination, brushes, swinging arms by which they are carried and which are provided with rollers, a block by which bodies are carried, wedges coöperating with the rollers to open the arms, for the purpose set forth, a vertically reciprocating bar by which the block and wedges are carried, and springs acting to retain the rollers in engagement with the wedges.

10. In a machine of the character described, in combination, brushes, swinging arms by which they are carried and which are provided with two sets of rollers, a block by which bodies are carried, wedges coöperating with one set of rollers to open the arms, a vertically reciprocating bar by which the block and wedges are carried, springs acting to retain the rollers in engagement with the wedges, and other wedges coöperating with the other set of rollers by which the arms may be opened widely and the brushes carried out of engagement with a body on the block.

11. In a machine of the character described, in combination, brushes, swinging arms by which they are carried, a block by which bodies are carried, wedges engaging the arms, for the purpose set forth, a bar by which the block and wedges are carried, springs acting to retain the rollers in engagement with the wedges, and a crank shaft and rods by which the bar is reciprocated vertically.

12. In a machine of the character described, in combination, brushes having an inward and downward rotary movement, swinging arms by which the brushes are carried, a block by which bodies are carried,

wedges engaging the arms, for the purpose set forth, a bar by which the block and wedges are carried, springs acting to retain the arms in engagement with the wedges, a crank shaft and rods by which the bar is reciprocated vertically, and driving connections between the crank shaft and the brushes.

13. In a machine of the character described, in combination, a frame having ways, brushes, shafts by which the brushes are carried, swinging arms in which the shafts are journaled, a block by which bodies are carried, wedges engaging the arms, for the purpose set forth, a bar, engaging the ways, by which the block and wedges are carried, springs acting to retain the arms in engagement with the wedges, a crank shaft and rods by which the bar is reciprocated on the ways, and driving connections between the crank shaft and the brush shafts.

14. In a machine of the character described, in combination, a frame, brushes, shafts by which the brushes are carried, swinging arms in which the shafts are journaled, a block by which bodies are carried, wedges engaging the arms, for the purpose set forth, a bar by which the block and wedges are carried, springs acting to retain the arms in engagement with the wedges, a crank shaft and rods by which the bar is reciprocated vertically, driving connections between the crank shafts and the brush shafts, and hand and power driving connections for the crank shaft.

15. In a machine of the character described, in combination, a frame, brushes, swinging arms in which the brushes are journaled, a block by which bodies are carried, wedges engaging the arms, for the purpose set forth, a bar by which the block and wedges are carried, springs acting to retain the arms in engagement with the wedges, means for imparting vertical reciprocatory movement to the bar and for rotating the brushes, and hand-operated means coöperating with the arms for moving the brushes outward away from the block.

16. In a machine of the character described, in combination, brushes, swinging arms by which they are carried, a vertically reciprocating block by which bodies are carried, means for causing the arms to swing inward and outward as the block moves upward and downward, to maintain uniform pressure of the brushes upon a body on the block, and means for imparting rotary movement to the brushes.

17. In a machine of the character described, in combination, brushes, swinging arms by which they are carried, a block by which bodies are carried, wedges having an angle of inclination corresponding with the block, for the purpose set forth, and means

for imparting vertical reciprocatory movement to the block and wedges.

18. In a machine of the character described, in combination, brushes, swinging arms by which they are carried, a block by which bodies are carried, wedges having an angle of inclination corresponding with the block, for the purpose set forth, a vertically reciprocating bar by which the block and wedges are carried, and means for imparting rotary movement to the brushes.
19. In a machine of the character described, in combination, brushes, swinging arms by which they are carried, a block by which bodies are carried, wedges having an angle of inclination corresponding with the block, for the purpose set forth, means for imparting vertical reciprocatory movement

to the block and wedges, and hand-operated means for swinging the arms outward and moving the brushes away from the block.

20. In a machine of the character described, in combination, brushes, swinging arms by which they are carried, a block by which bodies are carried, wedges having an angle of inclination corresponding with the block, said wedges coöperating with the arms, for the purpose set forth, a vertically reciprocating bar by which the block and wedges are carried, and other wedges also coöperating with the arms, by which the arms are moved outward away from the block.

In testimony whereof I affix my signature.

AUGUST M. WARM.
